(57) **CLAIM**

The ornamental design for a drug delivery device, substantially as shown and described.

DESCRIPTION

The patent or application file contains at least one drawing executed in color. Copies of this patent or patent publication with color drawing(s) will be provided by the Office upon request and payment of the necessary fee.

FIG. 1 is a rear view of a first embodiment of the drug delivery device;

FIG. 2 is a front view thereof;

FIG. 3 is a right side view thereof;

FIG. 4 is a left side view thereof;

FIG. 5 is a bottom view thereof;

FIG. 6 is a top view thereof; and

FIG. 7 is a perspective view thereof.

FIG. 8 is a rear view of a second embodiment of the drug delivery device;

FIG. 9 is a front view thereof;

FIG. 10 is a right side view thereof;

FIG. 11 is a left side view thereof;

FIG. 12 is a bottom view thereof;

FIG. 13 is a top view thereof; and,

FIG. 14 is a perspective view thereof.
